MASCARA CASE

Neil S. Waterman, Scarsdale, N. Y., assignor, by
mesne assignments, to Tarlen Corporation,
White Plains, N. Y., a corporation of New York

Application August 27, 1946, Serial No. 693,359

13 Claims. (Cl. 220—4)

1

This invention relates to new and useful improvements in cases, and has more particular reference to a mascara case.

The invention particularly proposes the construction of a mascara case from thermoplastic or thermo-setting materials so constructed that it has a hinge and a lock formed entirely from the thermoplastic material.

More particularly, the new mascara case has a base section and a top section hingedly connected together with a novel hinge formed entirely of the material from which these case sections are constructed. It is an object of this invention to so construct the hinged portions of the case sections that they may be formed by simple dies. It is another object of this invention to so construct the hinge that the two case sections may be assembled by merely engaging them together. They may be disassembled by forcing them apart.

The invention also proposes to so construct the case sections that locking elements are formed thereon which are capable of engaging each other to hold the case sections closed. It is an object of this invention to so construct the locking elements that they are formed entirely from the material of the case sections. Moreover, the locking elements are so formed that the case sections may be constructed with a simple molding die.

The invention also proposes to so design each of the case sections that they may be constructed with simple molding dies. The case sections may be provided with partitions for dividing off different chambers which are open in the same direction, for each of the case sections, to permit simple opening and closing of the molding dies.

Another object of this invention is the construction of an article as described which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a case constructed in accordance with this invention and illustrated in a closed position.

Fig. 2 is a perspective view of the case shown in Fig. 1 illustrated in an open position.

Fig. 3 is an enlarged plan view of the top section of the case as seen in Fig. 2.

2

Fig. 4 is an elevational view of Fig. 3.

Fig. 5 is an end view looking in the direction of the line 5—5 of Fig. 4.

Fig. 6 is an enlarged plan view of the base section of the case as seen in Fig. 2.

Fig. 7 is a side elevational view of Fig. 6 to which a portion of the top section has been added, positioned vertically so as to indicate the manner in which the hinged portions of the case sections may be connected together.

Fig. 8 is an end view looking in the direction of the line 8—8 of Fig. 7.

Fig. 9 is a horizontal sectional view as though taken on the line 9—9 of Fig. 7, but illustrated with the hinge elements of the case sections connected together.

Fig. 10 is a fragmentary side elevational view similar to Fig. 7, but disclosing a case constructed in accordance with another form of this invention.

Fig. 11 is a fragmentary end view of the case base section shown in Fig. 10.

The new case, in accordance with this invention, includes a molded case base section 10 and a molded case top section 11. The base section 10 has a base wall 12, flange-like side walls 13 having an opposed pair of studs 14 on their inner faces. The base section 10 is also provided with a back wall 16 and a horizontal partition 17 extending forwards from said back wall 16 and located between said side walls 13 for forming a compartment 18 for a mascara brush, schematically indicated by the dot and dash lines 19. This compartment 18 is open towards the front end of the case section 10.

The top section 11 is of a width to closely fit between said flange-like side walls 13. The top section 11 has a top wall 21, this wall 21 being at the top when the case is closed, as illustrated in Fig. 1. The top section 11 is also provided with end walls 22 and 23, side walls 24, and small openings 25 extended downwards from said top wall 21 and into said side walls 24 for receiving the studs 14. The studs 14 have beveled ends 26 directed towards the front of the case for slightly flexing said flange-like side walls 13 when studs 14 are engaged into the openings 25 so that the tips of said studs 14 engage against the bottom face of the top wall (see particularly Fig. 9) for holding the case sections pivotally together.

The horizontal partition 17 is located substantially midway of the height of the base sections 10. The top section 11 is positioned above the partition 17. A transverse wall 27 is formed across the side walls 24 of the top section 11

dividing off a small space 28 between the openings 25. A mascara cake 29, see Fig. 2, is mounted within the top section 11 between the walls 22, 24 and 27. The end wall 22 is of a sufficient height so as to extend down and close the open end between the flange-like side walls 13. A small flange 30 is formed upon the front top end of the top section 11 and is opposed to a small flange-like projection 31 formed upon the bottom of the front end of the base section 10 so as to be opposed to the flange 30 and to constitute grips so that the case sections may be easily opened and closed. The front wall 22 of the top section 11 has a slightly curved face 32 (see Fig. 1) to provide additional room for gripping the flange 30 and projection 31. The corner 34 of the top section 11, which is near the hinge of the case, is rounded and is adapted to mate with a curved edge 35 formed upon the top of the end wall 16 of the base section 10.

The top front corners of the flange-like side walls 13 are formed with notches 36 constituting latch elements. These notches 36 have downwardly and rearwardly beveled ends 37 (see Fig. 7) and beveled faces 38 (see Fig. 6) to facilitate the latching action. These notches 36 are complementary to bolt-like projections 39 formed upon the ends of the flange 30. The projections 39 have beveled faces 40 (see Fig. 4) and beveled ends 41 (see Fig. 3) facilitating the inter-engagement with the bevels of the notches 36.

It is an important feature of this invention that the case sections 10 and 11 may be molded in a simple molding die. It should be noted that the base section 10 has all openings and inclined faces directed towards the front of the case. For this reason a die may be constructed which separates upon a vertical plane through the centers of the studs 14. This vertical plane must terminate a short distance above the curved edge 35 of the rear wall 16. The sections of the die will now be openable right and left. The top section 10 has all of its openings and inclined faces directed upwards and downwards. For this reason it may be constructed with a simple die which opens up and down.

The case sections 10 and 11 are molded separately. They are then connected by placing the top section 11 in a vertical position while the bottom section 10 is in a horizontal position, as illustrated in Fig. 7. The case section 11 is then moved towards the left so that the studs 14 ride into the openings 25. The beveled faces 26 of the studs 14 will ride against the adjacent edges of the top wall 21 of the section 11 causing the flange-like side walls 13 to flex outwards momentarily, while the ends of the studs 14 snap across the bottom face of the top wall 21 of the section 11 to a position as illustrated in Fig. 9.

In Figs. 10 and 11 a modified form of case embodying this invention has been disclosed. In this form of case, the compartment 18 for the mascara brush 19 is formed by a mirror, schematically indicated by the dot and dash lines 45. This mirror is supported at each of its sides between vertically spaced horizontal strip portions 46 formed on the inner faces of the flange-like side walls 13. The spaces between the strip portions 46 are open to the front end of the case so that the strip portions 46 may be easily molded integral with the case base section with a simple molding die.

In other respects this form of the invention is identical to the previous form and like parts are identified by like reference numerals.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A case, comprising a molded case base section having a base wall and flange-like side walls having an opposed pair of studs on their inner faces, a molded case top section for fitting between said side walls and having a top wall, end walls and side walls and openings extended downwards from said top wall and into said side walls for receiving said studs, and said studs having beveled ends for slightly flexing said flange-like side walls when said studs are engaged into said openings so that the tips of said studs engage against the bottom face of said top wall for holding the case sections pivotally together.
2. A case, comprising a molded case base section having a base wall and flange-like side walls having an opposed pair of studs on their inner faces, a molded case top section for fitting between said side walls and having a top wall, end walls and side walls and openings extended downwards from said top wall and into said side walls for receiving said studs, and said studs having beveled ends for slightly flexing said flange-like side walls when said studs are engaged into said openings so that the tips of said studs engage against the bottom face of said top wall for holding the case sections pivotally together, said base section being provided with a back wall and a horizontal partition extending between said back wall and said flange-like side walls and forming a compartment open towards the front end of the case.
3. A case, comprising a molded case base section having a base wall and flange-like side walls having an opposed pair of studs on their inner faces, a molded case top section for fitting between said side walls and having a top wall, end walls and side walls and openings extended downwards from said top wall and into said side walls for receiving said studs, and said studs having beveled ends for slightly flexing said flange-like side walls when said studs are engaged into said openings so that the tips of said studs engage against the bottom face of said top wall for holding the case sections pivotally together, said flange-like side walls having notches formed in the top corners of its front end, and keeper projections from said case top section cooperative with said notches for releasably holding said case sections closed.
4. A case, comprising a molded case base section having a base wall and flange-like side walls having an opposed pair of studs on their inner faces, a molded case top section for fitting between said side walls and having a top wall, end walls and side walls and openings extended downwards from said top wall and into said side walls for receiving said studs, and said studs having beveled ends for slightly flexing said flange-like side walls when said studs are engaged into said openings so that the tips of said studs engage against the bottom face of said top wall for holding the case sections pivotally together, said flange-like side walls having notches formed in the top corners of the front end, and keeper projec-

tions from said case top section cooperative with said notches for releasably holding said case sections closed, said case top section being provided with a top flange opposed to a projection on the bottom of said case base section.

5. A case, comprising a molded case base section having a base wall and flange-like side walls having an opposed pair of studs on their inner faces, a molded case top section for fitting between said side walls and having a top wall, end walls and side walls and openings extended downwards from said top wall and into said side walls for receiving said studs, and said studs having beveled ends for slightly flexing said flange-like side walls when said studs are engaged into said openings so that the tips of said studs engage against the bottom face of said top wall for holding the case sections pivotally together, said flange-like side walls having notches formed in the top corners of the front end, and keeper projections from said case top section cooperative with said notches for releasably holding said case sections closed, said case top section being provided with a top flange opposed to a projection on the bottom of said case base section, said top flange being provided with the projections cooperative with said notches.

6. A case, comprising a molded case base section having a base wall, flange-like side walls having an opposed pair of studs on their inner faces, a back wall, and a horizontal partition extending forwards from said back wall and between said side walls forming a compartment open towards the front end of the case section, a molded case top section for fitting closely between said flange-like side walls and having a top wall, end walls and side walls and openings extended downwards from said top wall and into said side walls for receiving said studs, and said studs having beveled ends with the bevel faces directed towards the front of said case for slightly flexing said flange-like side walls when said studs are engaged into said openings so that the tips of said studs engage against the bottom face of said top wall for holding the case sections pivotally together.

7. A case, comprising a molded case base section having a base wall, flange-like side walls having an opposed pair of studs on their inner faces, a back wall, and a horizontal partition extending forwards from said back wall and between said side walls forming a compartment open towards the front end of the case section, a molded case top section for fitting closely between said flange-like side walls and having a top wall, end walls and side walls and openings extended downwards from said top wall and into said side walls for receiving said studs, and said studs having beveled ends with the bevel faces directed towards the front of said case for slightly flexing said flange-like side walls when said studs are engaged into said openings so that the tips of said studs engage against the bottom face of said top wall for holding the case sections pivotally together, the front ends of said flange-like side walls having notches, and projections complementary to said notches on the front end of said case top section for holding said case releasably closed.

8. A case, comprising a molded case base section having a base wall, flange-like side walls having an opposed pair of studs on their inner faces, a back wall, and a horizontal partition extending forwards from said back wall and between said side walls forming a compartment open towards the front end of the case section,

a molded case top section for fitting closely between said flange-like side walls and having a top wall, end walls and side walls and openings extended downwards from said top wall and into said side walls for receiving said studs, and said studs having beveled ends with the bevel faces directed towards the front of said case for slightly flexing said flange-like side walls when said studs are engaged into said openings so that the tips of said studs engage against the bottom face of said top wall for holding the case sections pivotally together, the front ends of said flange-like side walls having notches, and projections complementary to said notches on the front end of said case top section for holding said case releasably closed, said notches having faces directed frontwards of the case.

9. A case, comprising a molded case base section having a base wall, flange-like side walls having an opposed pair of studs on their inner faces, a back wall, and a horizontal partition extending forwards from said back wall and between said side walls forming a compartment open towards the front end of the case section, a molded case top section for fitting closely between said flange-like side walls and having a top wall, end walls and side walls and openings extended downwards from said top wall and into said side walls for receiving said studs, and said studs having beveled ends with the bevel faces directed towards the front of said case for slightly flexing said flange-like side walls when said studs are engaged into said openings so that the tips of said studs engage against the bottom face of said top wall for holding the case sections pivotally together, the front ends of said flange-like side walls having notches, and projections complementary to said notches on the front end of said case top section for holding said case releasably closed, said notches having faces directed frontwards of the case, certain of said faces being undercut.

10. A case, comprising a molded case base section having a base wall, flange-like side walls having an opposed pair of studs on their inner faces, a back wall, and a horizontal partition extending forwards from said back wall and between said side walls forming a compartment open towards the front end of the case section, a molded case top section for fitting closely between said flange-like side walls and having a top wall, end walls and side walls and openings extended downwards from said top wall and into said side walls for receiving said studs, and said studs having beveled ends with the bevel faces directed towards the front of said case for slightly flexing said flange-like side walls when said studs are engaged into said openings so that the tips of said studs engage against the bottom face of said top wall for holding the case sections pivotally together, the front ends of said flange-like side walls having notches, and projections complementary to said notches on the front end of said case top section for holding said case releasably closed, said notches having faces directed frontwards of the case, certain of said faces being undercut, said projections having faces directed upwards and downwards and opposed to the faces of said notches.

11. A case, comprising a molded case base section having a base wall and flange-like side walls having an opposed pair of studs on their inner faces, a molded case top section for fitting between said side walls and having a top wall, end walls and side walls and openings extended downwards from said top wall and into said side

walls for receiving said studs, and said studs having beveled ends for slightly flexing said flange-like side walls when said studs are engaged into said openings so that the tips of said studs engage against the bottom face of said top wall for holding the case sections pivotally together, and said flange-like side walls being provided with strip portions on their inner faces for supporting a mirror in a horizontal position to form a compartment open towards the front end of the case.

12. A case, comprising a molded case base section having a base wall and flange-like side walls having an opposed pair of studs on their inner faces, a molded case top section for fitting between said side walls and having a top wall, end walls and side walls and openings extended downwards from said top wall and into said side walls for receiving said studs, and said studs having beveled ends for slightly flexing said flange-like side wall when said studs are engaged into said openings so that the tips of said studs engage against the bottom face of said top wall for holding the case sections pivotally together, and said flange-like side walls being provided with strip portions on their inner faces for supporting a mirror in a horizontal position to form a compartment open towards the front end of the case, each flange-like side wall being provided with a pair of horizontal strip portions vertically spaced of each other.

13. A case, comprising a molded case base sec-

tion having a base wall and flange-like side walls having an opposed pair of studs on their inner faces, a molded case top section for fitting between said side walls and having a top wall, end walls and side walls and openings extended downwards from said top wall and into said side walls for receiving said studs, and said studs having beveled ends for slightly flexing said flange-like side walls when said studs are engaged into said openings so that the tips of said studs engage against the bottom face of said top wall for holding the case sections pivotally together, and said flange-like side walls being provided with strip portions on their inner faces for supporting a mirror in a horizontal position to form a compartment open towards the front end of the case, each flange-like side wall being provided with a pair of horizontal strip portions vertically spaced of each other, and the space between said strip portions being open towards the front of said case.
